UNITED STATES PATENT OFFICE.

JOHN VISTINE, OF CICERO, ILLINOIS.

VEGETABLE CUTTER.

Application filed May 11, 1923. Serial No. 638,318.

To all whom it may concern:

Be it known that I, JOHN VISTINE, a citizen of the United States of America, residing at Cicero, in the county of Cook and State of Illinois, have invented certain new and useful Improvements in Vegetable Cutters, of which the following is a specification.

This invention relates to certain new and useful improvements in vegetable cutters and has for its primary object to provide a cutter casing carrying a laterally extending bracket arm adapted for mounting upon a convenient support such as a table top, the cutter and operating mechanism therefor being supported on the bracket arm.

With the above and other objects in view as the nature of the invention is better understood, the same consists of the novel form, combination and arrangement of parts hereinafter more fully described, shown in the accompanying drawing and claimed.

In the drawing, wherein like reference characters designate corresponding parts throughout the several views,

Figure 1 is a side elevational view, partly broken away of a vegetable cutter constructed in accordance with the present invention, the lateral bracket supporting arm therefor being illustrated as mounted upon a support, such as a table top,

Figure 2 is a top plan view of the device,

Figure 3 is a vertical sectional view taken on line III—III of Fig. 1 showing the driving means for the disk cutter,

Figure 4 is a horizontal sectional view taken on line IV—IV of Fig. 3 showing the arcuate extension carried by the supporting bracket to which the upper casing section is secured, and

Figure 5 is a cross-sectional view taken on line V—V of Fig. 3 showing the disk cutter and the cutter blades carried thereby.

Referring more in detail to the accompanying drawing, there is illustrated a vegetable cutter including a horizontal bracket 1 bifurcated at one end as at 2 to enclose a table top or other support 3 during mounting thereof for use, a thumb screw 4 being associated with the bifurcated end of the bracket 1 for clamping the same in position upon the support. The other end of the bracket 1 carries a vertically disposed arcuate extension 5 that flatly engages the outer face of an upper casing section 6 and is secured thereto as at 7, as shown in Fig. 3. A

lower casing section 8 encloses at its upper end, the lower end of the upper casing section 6 and is supported by an arm 9 anchored as at 10 to the bracket 1, the upper casing section 6 being closed as at 11 while the lower casing section 8 is open at its lower end as shown in Fig. 3.

The outer upper end of the arcuate extension 5 carries an extension arm 12 overlying the upper closed end 11 of the casing section 6 and terminates axially thereof within a bearing 13, a corresponding arm 14 extending from the lower end of the extension 5 and terminating in a bearing 15 axially of the casing.

A vertical shaft 16 is journaled in the bearings 13 and 15 of the extension arms 12 and 14, the upper end of the shaft 16 carrying a fixed pinion 17 meshing with a beveled gear 18 that is journaled in the outer end 19 of an arcuate arm 20 projecting upwardly from the bracket 1 and overlying the cutter casing, the gear 18 carrying a handle 21 to effect rotation thereof.

A disk 22 is secured to the lower end of the shaft 16 below the arm 14, the disk being provided with diametrically opposite radial slots 23 over which the edges of cutting blades 24 extend.

Vegetables are introduced into the upper casing section 6 through the opening afforded by the hinged cover section 11^a and upon rotating the shaft 16 through the meshing gears 17 and 18, the disk 22 is rotated for moving the vegetables into engagement with the arm 14, the cutter blades 24 successively passing the arm 14 at a point beneath the same for slicing or cutting the vegetables that fall through the slotted openings 23.

While there is herein shown and described the preferred embodiment of the present invention, it is nevertheless to be understood that minor changes may be made therein without departing from the spirit and scope of the invention as claimed.

What is claimed as new is:—

1. In a vegetable cutter, a casing, a lateral bracket arm projecting therefrom for mounting on a support, a vertical shaft journaled in the casing, a disk cutter carried by the lower end thereof, means for rotating the shaft, the connection between the casing and bracket arm including an arcuate plate extension carried by the bracket arm secured to the casing, said disk cutter including a plate having opposite radial openings, a

knife blade overlying each opening, and lateral arms carried by the arcuate plate having bearings at the ends in which the shaft is journaled.

5 2. In a vegetable cutter, a casing, a lateral bracket arm projecting therefrom for mounting on a support, a vertical shaft journaled in the casing, a disk cutter carried by the lower end thereof, means for rotating the 10 shaft, the connection between the casing and bracket arm including an arcuate plate ex-

tension carried by the bracket arm secured to the casing, said disk cutter including a plate having opposite radial openings, a knife blade overlying each opening, and lateral arms carried by the arcuate plate having bearings at the ends in which the shaft is journaled, the lower arm being disposed above the cutting disk and forming an abutment cooperating with the knife blades.

15

In testimony whereof I affix my signature.
JOHN VISTINE.
